UNITED STATES PATENT OFFICE.

ABRAHAM L. VAN BUSKIRK, OF IDAHO FALLS, IDAHO.

EVAPORATIVE REFRIGERATOR.

1,073,375.

Specification of Letters Patent. Patented Sept. 16, 1913.

Application filed November 30, 1912. Serial No. 734,354.

To all whom it may concern:

Be it known that I, ABRAHAM L. VAN BUSKIRK, a citizen of the United States of America, residing at Idaho Falls, in the 5 county of Bonneville and State of Idaho, have invented new and useful Improvements in Evaporative Refrigerators, of which the following is a specification.

This invention relates to improvements in 10 refrigerators or cooling cabinets and has particular application to a device of the class described employing a liquid cooling agent or refrigerating medium as distinguished from a solid cake of cooling medium such, 15 for instance, as a block of ice.

In carrying out the present invention, it 20 is my purpose to provide a refrigerator or cooling cabinet wherein vegetables and other eatables of a perishable nature may be maintained fresh and cool without the necessity of using ice or other cooling matter in block form.

It is also my purpose to provide a refrigerator wherein by means of a number of 25 bags each containing a cooling agent, the interior of the refrigerator will be kept cold.

Furthermore, I aim to provide a refrigerator the top, rear and side walls of which will be constructed in such manner as to 30 form chambers for the reception of flexible bags each containing a cooling agent by means of which the interior of the refrigerator is maintained cold, thereby enabling the entire interior chamber of the refrigerator, 35 ator to be used for storing purposes.

With the above and other objects in view, the invention consists in the construction, combination and arrangement of parts hereinafter set forth in and falling within the 40 scope of the claims.

In the accompanying drawing; Figure 1 is a view in front elevation of a refrigerator constructed in accordance with the present invention, the door being shown in open position and broken away. Fig. 2 is a transverse sectional view on the line 2—2 of Fig. 1 with the door in closed position. Fig. 3 is a vertical section view on the line 3—3 of Fig. 1, and Fig. 4 is a detail perspective 50 view of a portion of one of the bags.

Referring now to the accompanying drawing in detail, the numeral 1 indicates the bottom of the refrigerator composed, in the present instance, of two sections of material 55 2, 3 appropriately spaced apart to form a chamber designed to contain a packing of

cork 4 or other heat insulating material, legs 5 depending from the bottom to hold the same a suitable distance above the floor. Upstanding from the bottom 1 and suitably fastened thereto are side walls 6, 6 and a rear wall 7, each formed of two sections of material 8, 8 spaced apart a suitable distance in parallelism to form a chamber 9, while fastened in any suitable manner to the upper 60 edges of the side and rear walls is the top wall 10 of the refrigerator also composed of two sections of material 11, 11 suitably spaced apart to provide a chamber 12. Hingedly connected to the outer edge of one 65 of the end walls 6 is the door 13 of the refrigerator, the latter being formed of two parallel plates spaced apart a suitable distance to form a chamber designed to contain a quantity of heat insulating material such, 70 for instance, as cork 14.

The chambers 9, 9 and 12 of the side and rear and top walls respectively are each adapted to contain a flexible bag 15 constructed of any suitable porous material 80 such as canvas or the like and provided with a filling nipple 16 whereby a quantity of water and alcohol or water and ammonia may be poured thereinto, while the outer walls of said chambers are perforated as 85 shown to permit a free circulation of air around the bags. Extending through the top wall 10 of the refrigerator is a suitable ventilating pipe 17. Any suitable means, such for instance, as cages 18 may be employed to prevent the bags from contacting with the adjacent walls of the chambers formed by the strips or sections of material of the walls of the refrigerator, while a drip pan 19 is deposited at the lower end of 90 each chamber 9 so as to catch any liquid that may percolate through the bags. It will be noted that the chambers 9 and 12 are in open communication with one another, thereby equalizing the cold air about 95 the food compartments of the refrigerator. In the present instance, the food compartment is divided by means of a partition or shelf 20, but such shelf may be eliminated if desired, or the food compartment may be 100 divided into as many compartments as found convenient.

From the foregoing description taken in connection with the accompanying drawing, the construction and manner of employing 105 my improved refrigerator or cooling cabinet will be readily apparent.

In operation, the liquid within the bags percolates therethrough and is evaporated by the air within the chambers, the wire cages holding the bags spaced apart from the walls of the chambers and so facilitating the circulation of the air and the consequent evaporation. The alcohol or ammonia within the water freely commingles with the latter and upon percolating through the bags and evaporating extracts the heat units from the surrounding air so as to maintain the latter cool.

It will be seen that I have provided a refrigerator wherein the food compartment is at all times maintained cold without the use of ice or the like and whereby the cold air surrounding such food compartment is equalized.

While I have herein shown and described one preferred form of my invention by way of illustration, I wish it to be understood that I do not limit or confine myself to the precise details of construction herein described and delineated, as modification and variation may be made within the scope of the claims and without departing from the spirit of the invention.

I claim:

1. A refrigerator including side, top and end walls each formed of two independent sections of material spaced apart to provide

a chamber, all of said chambers having communication with one another, a porous bag disposed within each chamber and containing a cooling agent, and means holding each bag suspended within the respective chamber and the sides of the bag out of contact with the adjacent walls of the chamber.

2. A refrigerator including side, top and end walls each formed with a chamber, all of said chambers having communication with one another, a porous bag disposed within each chamber and containing a cooling agent, and means holding each bag suspended within the respective chamber and the sides of the bag out of contact with the adjacent walls of the chamber.

3. A refrigerator including side, top and end walls each formed with a chamber, all of said chambers having communication with one another, a porous bag disposed within each chamber and containing a cooling agent, and a cage holding each bag suspended within the respective chamber and the sides of the bag out of contact with the adjacent walls of the chamber.

In testimony whereof I affix my signature in presence of two witnesses.

ABRAHAM L. VAN BUSKIRK.
